(57) **CLAIM**

The ornamental design for a winder of launching apparatus for spinning top toy as shown and described.

DESCRIPTION

FIG. 1 is a front elevational view of a winder of launching apparatus for spinning top toy, showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front, right-side, top perspective view thereof;

FIG. 8 is a front, right-side, top perspective view thereof;

FIG. 9 is a rear, left-side, top perspective view thereof; and,

FIG. 10 is a rear, left-side, bottom perspective view thereof.

1 Claim, 10 Drawing Sheets
